OIL DISPENSING COMB

Lawrence H. Pepin, San Diego, Calif.

Application August 11, 1947, Serial No. 767,911

6 Claims. (Cl. 132—13)

1

My invention relates to an oil dispensing comb, more particularly for use in automatically applying hair oil to a person's hair and scalp when combing the hair. The objects of my invention are:

First, to provide an oil dispensing comb of this class which so controls hair oil that the desired amount of oil may be uniformly applied to a person's hair with little attention to the application of said oil when combing the hair.

Second, to provide an oil dispensing comb of this class which delivers the oil directly to the scalp of a person's head if desired.

Third, to provide an oil dispensing comb of this class having novel oil control means whereby only certain quantities of oil as desired are dispensed adjacent to the tooth area of the comb.

Fourth, to provide an oil dispensing comb of this class in which the control mechanism therein reduces to a minimum the leakage of oil from said comb.

Fifth, to provide an oil dispensing comb of this class in which the oil may be very quickly put under pressure.

Sixth, to provide an oil dispensing comb of this class having a compact oil reservoir integral with the comb and slight compression means in the end of the reservoir whereby the comb is very conveniently operated in the dispensing of oil to a person's hair.

Seventh, to provide an oil dispensing comb of this class which is very simple and economical in construction, efficient in operation, and which will not readily deteriorate or get out of order.

With these and other objects in view as will appear hereinafter, my invention consists of certain novel features of construction, combination and arrangement of parts, and portions as will be hereinafter described in detail and particularly set forth in the appended claims, reference being had to the accompanying drawings and to the characters of reference thereon, forming a part of this application in which:

Figure 1 is a side elevational view of my oil dispensing comb showing portions broken away and in section to amplify the illustration, Figure 2 is a fragmentary side elevational view of a modified form of my oil dispensing comb showing portions broken away and in section to amplify the illustration, Figure 3 is an enlarged transverse sectional view taken on the line 3—3 of Figure 1, and Fig. 4 is an enlarged fragmentary sectional view taken on the same plane as Fig. 1.

Similar characters of reference refer to similar parts and portions throughout the several views of the drawings:

The comb body 1, dispenser casing 2, plunger 3, spring 4, plunger cover 5, and reservoir filler

2

cap 6 constitute the principal parts and portions of my oil dispensing comb.

The comb body 1 is a hollow cylindrical member having comb teeth 1—a integral therewith. These comb teeth 1—a are each provided with a central oil conducting orifice 1—b extending from the ends 1—c to the bore 1—d of the body 1 which bore 1—d provides an oil reservoir adapted to supply oil through the orifice portions 1—b to the ends 1—c of the teeth 1—a. One end of the comb body 1 is fitted with a reservoir filler cap 6 and positioned in the opposite end of the comb body 1 is the dispenser casing 2. This dispenser casing 2 is a hollow cylindrical casing having a reduced bore portion 2—a therein in which the tapered shank 3—a of the plunger 3 is closely fitted and, axially movably mounted. It will be here noted that the tapered shank 3—a fits the bore 2—a forming a valve while clearance of the plunger head 3—b permits air passage therearound. The dispenser case 2 is provided with an enlarged bore portion 2—b in which the enlarged head 3—b of the plunger is reciprocally mounted, and the spring 4 is positioned in the dispenser casing 2, engaging the plunger 3 tending to force the same outwardly at the end of said casing 2 through which said reduced bore 2—a extends. In connection with the comb body 1 surrounding the end of the dispenser casing 2 is the plunger cover 5 which covers the plunger 3, all as shown best in Figure 1 of the drawings.

In the construction of my comb the comb body 1 may be constructed substantially as shown in Figure 2 if desired wherein the reservoir 1—d communicates with orifices 1—e intermediate teeth 1—a. This arrangement provides for direct lubrication of a person's hair without transferring or delivering the oil directly to the scalp at the roots of the hair.

The operation of my oil dispensing comb is substantially as follows: When the reservoir portion 1—d of the comb body 1 is supplied with oil and it is desired to put pressure on the same and cause oil to flow through the orifices 1—b to the ends 1—c of the teeth 1—a, the plunger cover 5 is removed and the plunger is pressed inwardly toward the reservoir 1—d. The tapered shank 3—a passing through the reduced bore 2—a of the dispenser casing 2 provides clearance therearound permitting a small amount of air to pass inwardly of the dispenser casing 2 when the enlarged head portion 3—b of said plunger 3 reciprocates in the bore portion 2—b of the dispenser casing 2. Longitudinal inward movement of plunger 3 causes the oil in the reservoir 1—d to be slightly compressed and with each inward movement a small amount of air passes around the tapered shank 3—a of the plunger 3.

displacing fluid relieved from the reservoir 1—d through the orifices 1—b or 1—e as shown in Figures 1 and 2 of the drawings. When the plunger 3 is in the extended position as shown in Figure 1 of the drawing the reservoir 1—d is sealed at opposite end and the very fine capillary orifices 1—b in the comb body 1 prevent oil from leaking out of my oil dispensing comb. With each inward reciprocal movement of the plunger 3 the spring 4 is compressed whereupon it tends to return the plunger 3 to its original position as shown in Figure 1 of the drawings.

When it is desired to refill the reservoir 1—d the reservoir filler cap 6 is removed and hair oil is placed in the reservoir 1—d and then the reservoir filler cap 6 is tightly replaced.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. An oil dispensing comb having a plurality of spaced teeth, oil conductors for supplying oil to the ends of said teeth, a reservoir communicating directly with said conductors for supplying oil thereto, and a plunger having a tapered shank portion axially movably mounted in the end of said reservoir and a tapered seat for said shank whereby longitudinal movement of said plunger provides slight pressure on the oil in said reservoir and said tapered shank portion admits air therearound to displace oil dispensed from said reservoir to the teeth of said comb.

2. An oil dispensing comb having a plurality of spaced teeth, oil conductors for supplying oil to the ends of said teeth, a reservoir communicating directly with said conductors for supplying oil thereto, and a plunger having a tapered shank portion axially movably mounted in the end of said reservoir and a tapered seat for said shank whereby longitudinal movement of said plunger provides slight pressure on the oil in said reservoir and said tapered shank portion admits air therearound to displace oil dispensed from said reservoir to the teeth of said comb, a spring tending to hold said plunger outwardly.

3. An oil dispensing comb having a plurality of spaced teeth, oil conductors for supplying oil to the ends of said teeth, a reservoir communicating directly with said conductors for supplying oil thereto, and a plunger having a tapered shank portion axially movably mounted in the end of said reservoir and a tapered seat for said shank whereby longitudinal movement of said plunger provides slight pressure on the oil in said reservoir and said tapered shank portion admits air therearound to displace oil dispensed from said reservoir to the teeth of said comb, a spring tending to hold said plunger outwardly, said plunger having an enlarged head portion inwardly of said tapered shank portion engaging said spring and forming a compression piston for said oil.

4. An oil dispensing comb having a plurality of spaced teeth, oil conductors for supplying oil to the ends of said teeth, a reservoir communicating directly with said conductors for supplying oil thereto, and a plunger having a tapered shank portion axially movably mounted in the

end of said reservoir and a tapered seat for said shank whereby longitudinal movement of said plunger provides slight pressure on the oil in said reservoir and said tapered shank portion admits air therearound to displace oil dispensed from said reservoir to the teeth of said comb, a spring tending to hold said plunger outwardly, said plunger having an enlarged head portion inwardly of said tapered shank portion engaging said spring and forming a compression piston for said oil, a dispenser casing in which said plunger is reciprocally mounted having a bore portion closely fitting the head of said plunger and supporting said spring therein.

5. An oil dispensing comb having a plurality of spaced teeth, oil conductors for supplying oil to the ends of said teeth, a reservoir communicating directly with said conductors for supplying oil thereto, and a plunger having a tapered shank portion axially movably mounted in the end of said reservoir whereby longitudinal movement of said plunger provides slight pressure on the oil in said reservoir and said tapered shank portion admits air therearound to displace oil dispensed from said reservoir to the teeth of said comb, a spring tending to hold said plunger outwardly, said plunger having an enlarged head portion inwardly of said tapered shank portion engaging said spring and forming a compression piston for said oil, a dispenser casing in which said plunger is reciprocally mounted having a bore portion closely fitting the head of said plunger and supporting said spring therein, said dispenser casing having a tapered reduced bore portion adapted to fit said tapered shank portion of said plunger for closing said reservoir against the inlet of air when said plunger is extended.

6. An oil dispensing comb having a plurality of spaced teeth, oil conductors for supplying oil to the ends of said teeth, a reservoir communicating directly with said conductors for supplying oil thereto, and a plunger having a tapered shank portion axially movably mounted in the end of said reservoir whereby longitudinal movement of said plunger provides slight pressure on the oil in said reservoir and said tapered shank portion admits air therearound to displace oil dispensed from said reservoir to the teeth of said comb, a spring tending to hold said plunger outwardly, said plunger having an enlarged head portion inwardly of said tapered shank portion engaging said spring and forming a compression piston for said oil, a dispenser casing in which said plunger is reciprocally mounted having a bore portion closely fitting the head of said plunger and supporting said spring therein, said dispenser casing having a tapered reduced bore portion adapted to fit said tapered shank portion of said plunger for closing said reservoir against the inlet of air when said plunger is extended, a cover for said plunger engaging said casing.
